UNITED STATES PATENT OFFICE

142,598

DESIGN FOR AN ELECTRIC HEATER

William R. Tuttle, Riverside, Ill., assignor to
Tuttle & Kift, Inc., Chicago, Ill., a corporation
of Illinois

Application December 7, 1944, Serial No. 116,778

Term of patent 14 years

(Cl. D81—25)

To all whom it may concern:

Be it known that I, William R. Tuttle, a citizen of the United States, residing at Riverside, in the county of Cook, State of Illinois, have invented a new, original, and ornamental Design for an Electric Heater, of which the following is a specification, reference being had to the accompanying drawing, forming part thereof.

Fig. 1 is a top plan view of an electric heater showing my new design; and

Fig. 2 is an elevational view thereof taken from a position at the right of Fig. 1 and normal to the lower arm of Fig. 1.

The dominant features of the design reside in the portions shown in full lines.

I claim:

The ornamental design for an electric heater, as shown and described.

WILLIAM R. TUTTLE.
